UNITED STATES PATENT OFFICE.

JOHN R. MITCHELL, OF CHICAGO, ILLINOIS, ASSIGNOR TO WILLIAM H. MINER, OF CHAZY, NEW YORK.

SIDE BEARING FOR RAILWAY-CARS.

1,290,285.

Specification of Letters Patent.

Patented Jan. 7, 1919.

Application filed June 9, 1917. Serial No. 173,879.

To all whom it may concern:

Be it known that I, JOHN R. MITCHELL, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

The object of my invention is to provide a simple, efficient and laterally oscillatable side bearing.

In the drawing forming a part of this specification, Figure 1 is a longitudinal vertical section of a side bearing embodying my invention. Fig. 2 is a cross section taken on the line 2—2 of Fig. 1. Fig. 3 is an end view of the axle and surrounding parts illustrated in detail. Fig. 4 is a cross sectional view of a modification.

In the drawings, the numeral 10 indicates an upper or body bolster of a railway car shown in cross section. A lower or truck bolster is shown in cross section as indicated by the numeral 11. To one of said bolsters, preferably the body bolster 10, the side bearing 12 is secured. The bearing is provided with a base member 13 consisting of a plate 14 which is engaged to the bolster by suitable means, as for instance, the rivets 15, the said base member being provided with upstanding spaced apart sides 16—16, perforated as indicated at 17, to receive the ends of an axle 18. The ends of the axle 18, as indicated at the numeral 19, are flattened in order to permit their entry from above into the perforations 17 in the side walls 16 of the base member, and when so entered the surrounding metal is in substantially the conformation shown by the dotted lines in Fig. 3 of the drawings.

When in position the said metal, by means of a suitable tool, is driven into position, as illustrated in Fig. 3 of the drawings, and grips or clamps the ends of the axle firmly within the perforations 17. A roller 20 is mounted upon the axle 18, the same being preferably of a general cylindrical shape and provided with an axial opening 21. Within said opening a sleeve 22 is mounted, the said sleeve being perforated lon-

gitudinally, as indicated at 23, for the passage of the axle 18. The said sleeve 22 has a curved bearing face 24 which extends from end to end of said sleeve and is adapted to be engaged by the inner similarly curved bearing face 25 surrounding the opening 21 through the roller 20. The opening 21 is, throughout the roller, of a larger diameter than the largest diameter of the sleeve 22. This permits the use of a one-piece integral roller of strong construction and allows the entry of a sleeve having curved bearing faces therein.

When the parts are assembled as shown in Fig. 2 of the drawings, a free space, as indicated by the numeral 26, is formed between the bearing face of the sleeve upon one side and the adjacent inner bearing face of the roller 20. In relative movement of the bolsters the opposed bolster, as for instance, the upper bolster 10, will engage the roller and cause the same to revolve having its bearing only upon the adjacent, or as illustrated in the drawings, the upper portion of the sleeve, as indicated by the numeral 27 in Fig. 1 of the drawings, and will revolve upon said sleeve riding free at the other portions thereof.

Upon deflection of the bolsters under load the roller may oscillate laterally to accommodate its bearing face to the flat opposed bearing plate 28 upon the face of the opposed bolster 10, and its position in lateral oscillation in one direction is indicated by the dotted lines referenced 29 in Fig. 2 of the drawings.

Thus I have provided a strong, one-piece roller adapted to oscillate laterally upon an axle which is relatively fixed, that is, which does not laterally oscillate and using a one-piece sleeve insertible through the ends of the roller and having a curved contacting bearing face with the roller to permit such lateral oscillation. In assembling the parts the sleeve is inserted in the roller and the axle mounted in the sleeve whereupon the parts thus assembled may be mounted in the base member and the axle secured therein against accidental displacement.

In the modification shown in Fig. 4 of the drawings, a bolster is indicated at the numeral 40, the base member at 41, having the bottom plate 42 suitably secured to the bolster by the rivets 43 and having the up-

standing sides 44 perforated as at 45, to receive the flattened ends 46 of the axle 47. A sleeve 48 is mounted upon the axle and extends through the longitudinal opening 49 provided in the substantially cylindrical roller 50. The opening 49 at its smallest diameter is larger than the greatest diameter of the sleeve 48. The construction is the same as that shown in Figs. 1, 2 and 3 of the drawings except that the sleeve has a bearing face 51 that is concave from end to end instead of convex, as shown in the preferred form illustrated in the other figures of the drawings, and likewise, the inner bearing face 52 of the roller is convex instead of concave, as shown in the preferred embodiment of my invention. In the modified form the roller may oscillate laterally upon deflection of the bolsters, and one position that it may assume in such lateral oscillation is indicated by the dotted lines referenced 53 in said Fig. 4 of the drawings.

In both embodiments of my invention illustrated in the drawings, the sleeve which constitutes an inner element in the roller and the said roller have inter-engaging surfaces which are curved at right angles to the outer curved surfaces of the roller.

I claim:

30 1. In a side bearing for railway cars, a base member, a roller associated therewith, an axle to support the roller in the base member, the roller being provided with a perforation from end to end to receive the axle, the axle having a curved bearing face to permit the lateral oscillation of the roller upon the axle, the greatest diameter of the axle and said bearing face being less than the smallest diameter of the perforation in 40 said roller.

2. In a side bearing for railway cars, a base member, a roller associated therewith, an axle to support the roller in the base member, a sleeve mounted on said axle, the 45 roller having a perforation to receive said axle and sleeve, the sleeve being provided with a curved bearing face to permit the lateral oscillation of the roller thereon, the largest diameter of said sleeve being less than the smallest diameter of the perforation in 50 the roller.

3. In a side bearing for railway cars, in combination: a base member; a one-piece roller associated therewith; an axle to sup-

port the roller in the base member; the axle 55 being provided with a curved bearing face, the roller having a perforation to receive the axle and having an internal curved bearing face to engage the axle, the said axle being insertible through the ends of the 60 roller, the roller having lateral oscillating movement upon said axle.

4. In a roller side bearing for railway cars, the combination of a member adapted to be secured to a bolster or the like, of a 65 supporting axle carried by said member, an inner element mounted on said axle, a roller rotatable on said element, said element and roller having engaging surfaces curved at right angles to the curved surface of the 70 roller to permit the lateral oscillation of the roller thereon.

5. In a roller side bearing for railway cars, the combination of a member adapted to be secured to a bolster or the like, of a 75 supporting axle carried by said member, an inner element mounted on said axle, a roller rotatable on said element, said element and roller having engaging surfaces curved at right angles to the curved surface of the 80 roller to permit the lateral oscillation of the roller thereon, one of said engaging surfaces being concave and the other convex.

6. In a roller side bearing, in combination: a member adapted to be secured to a 85 bolster or the like; a supporting axle carried by said member; inner and outer rollers rotatably mounted on said axle; said rollers having engaging surfaces curved about axes at right angles to the axes of the 90 rollers and being rotatable relatively to each other.

7. In a side bearing, in combination: a member adapted to be secured to a bolster or the like; a supporting axle carried by said 95 member; an inner rotatable member carried on said axle; an outer rotatable member carried on said inner member and rotatable thereon; the inner member being loosely received in the outer member and one of said 100 members having a curved face engaging the other of said members to permit the lateral oscillation of the outer member in reference to the axle.

In witness that I claim the foregoing I 105 have hereunto subscribed my name this 19th day of May, 1917.

JOHN R. MITCHELL.
